UNITED STATES PATENT OFFICE.

MAGNUS W. TURNQUIST, OF CHICAGO, ILLINOIS

PHONOGRAPH.

1,294,850.

Specification of Letters Patent. Patented Feb. 18, 1919.

Application filed January 4, 1918. Serial No. 210,344.

To all whom it may concern:

Be it known that I, MAGNUS W. TURNQUIST, a citizen of the United States, and a resident of Chicago, county of Cook, and State of Illinois, have invented certain new and useful Improvements in Phonographs, of which the following is declared to be a full, clear, and exact description.

This invention relates to phonographs and is in the nature of an improvement upon the repeat mechanism (with certain novel features added thereto) shown and described in my prior Patent No. 1,249,251, issued December 4, 1917, for improvement in phonographs.

One of the objects of the present invention is to simplify and otherwise improve upon the repeat mechanism shown in my prior patent. Another object is to provide simple and efficient means for controlling the number of times that the musical selection is repeated, and for automatically stopping the mechanism when the piece has been played through the predetermined number of times. Another object is to provide a phonograph with controlled repeating mechanism actuated by the turn table-drive shaft of the phonograph. Another object is to provide improved means in a repeat mechanism whereby record disks turn table or record of large or small diameter may be used.

Other objects and advantages will occur in the course of this specification and with all of said objects and advantages in view, this invention consists in the several novel features of construction, arrangement and combination of parts hereinafter fully set forth and more particularly defined in the claims.

The invention is clearly illustrated in the drawings accompanying this specification in which:

Figure 1, is a plan of the repeat mechanism and a fragment of the tone arm and connections, the turn table having been removed from the view; Fig. 2, is a view partly in side elevation and partly in vertical cross section, taken on the line 2-2 of Fig. 1; Fig. 3, is a detail vertical longitudinal section taken on the line 3-3 of Fig. 1; Fig. 4, is a detail vertical longitudinal section taken on the line 4-4 of Fig. 1; Fig. 5, is a detail vertical section taken on the line 5-5 of Fig. 1; Fig. 6, is a detail horizontal section taken on the

line 6-6 of Fig. 4; Fig. 7, is a detail horizontal section taken on the line 7-7 of Fig. 5; Fig. 8, is an end view of the control mechanism shown in Fig. 4, looking from below; Fig. 9, is a detail vertical cross section taken on the line 9-9 in the Fig. 1, and Fig. 10, is a perspective view of a slightly modified form of the adjustment mechanism for accommodating the device for large and small record disks.

Referring to said drawings, the reference character A designates the top of the phonograph cabinet or case of ordinary construction in which is contained the usual motor, (a fragment of which is shown at B) for operating the phonograph mechanism. In accordance with the usual and common practice, said motor drives a spindle or shaft 7, to which is secured a sleeve 8, that carries 75 the turn table 9. The upper face of the turn table is usually provided with a felt cover 10, and the usual spindle 11, projects up from the table at its axis of rotation.

The tone arm 13, is rotatively mounted 80 on a vertical axis, supported by the cabinet in any suitable manner, and said tone arm overhangs the turn table as usual. It is provided with any of the ordinary and well known reproducers 14, which is hingedly 85 connected to the tone arm by a tubular bracket 15, which is pivotally connected with the tone arm on a horizontal axis. The stylus or needle 16, is employed in connection with the reproducer, as is common, and 90 travels in a spiral groove in the record disk 17. The horizontally swinging tone arm 13, is connected with the horn or tune chamber in accordance with any of the well known ways and during the operation of the phonograph, (while reproducing a musical selection) the tone arm travels in the direction indicated by the arrow a, thereon in Fig. 1, while the disk itself rotates in the direction indicated by the arrow b, thereon.

Secured to the tone arm is a bracket 19, which, in the embodiment of the invention shown herein, projects down from the lower end of the tone arm from a point near its vertical portion, and journaled in said 105 bracket is a spindle 22, which has an enlarged head 21, at one end, bearing against one side of the bracket 19, and a pin or other cross piece 21^a, at the other end of the spindle 22, holds said spindle against endwise 110 movement relative to the bracket. Fixedly secured to said spindle 22, is a frame shift-

ing arm 23, which underlies the turn table and projects forward along the under side of the tone arm. Near its forward end a grooved roller 26, is journaled upon the frame shifting arm 23, and rolls upon a track 27, that forms part of an oscillatory and reciprocatory frame C. The free end of the frame shifting arm 23, carries a friction roller 48, which, during the return movements of the tone arm, bears against the under side of the turn table 9, preferably said friction roller 48, is connected to the arm 23, by a spring member 48^a, made of a piece of flat spring metal secured to the end of the arm 23, and having a spindle 48^b, secured upon its end, which spindle acts as the shaft for the friction roller 48.

The frame shifting arm 23, is angularly adjustable with respect to the spindle 22, and the set screw 21^a, is threaded in the head 21, of the spindle 22, and bears against a piece of fiber or the like 21^b, which is interposed between the upturned end 23^a, of the arm 23, and the set screw 21^a. By reason of this angular adjustability of the arm 23, the position of the friction roller 48, may be adjusted to accommodate itself to turn tables and records of different diameters. Fixedly secured to the head 21, of the spindle 22, is a reproducer lifting arm 25, the free end of which underlies the free end of the tubular bracket 15, and acts to swing said bracket upward and therewith the reproducer and stylus, whenever the arm 23, is swung upward by the track 27, of the frame C.

The oscillatory and reciprocatory frame C, has aligned shafts or spindles 28, 29, which are slidably and rotatably mounted in brackets 30, which, in the embodiment of the invention shown, are formed by striking up the metal of a base plate A¹. Said frame C, has two shift plate supporting arms 31, 31^a, which extend on opposite sides of the spindle 7, and have fingers 33, 34, that are adapted to engage with the thread of a worm or screw 32^a, mounted on the spindle 7. As in my prior patent, the fingers 33, 34, are arranged to be alternatively brought into engagement with the upper end of the thread of the worm or screw, and moved in a downward direction by said screw, whereby the frame C, is rocked upon its shafts 28, 29, to effect the raising and lowering of the stylus, and the friction wheel 48. The worm or screw 32^a, is a left handed one inasmuch as the turn table and screw rotate in a "clock wise" direction.

Fulcrumed upon the arms 31, 31^a, of the frame C, are shift plates 42, 43, that are arranged to be engaged by one or more pins or shoulders 45, carried by the worm 32^a, to effect the reciprocatory movements of the frame C. Said shift plates are held against lengthwise movement relative to the frame C, as, for instance, by providing circumfer-

ential grooves in the arms 31, 31^a, of the frame C, which grooves receive downturned split ears or lugs 42^a, of the plates 42, 43. Said plates have parts 44, either one of which is normally in position to be engaged by one or the other of the shoulders 45, except that it is held above the plane traversed by said shoulders until the moment that the tone arm, and parts carried thereby, have reached either limit of travel, whereupon said plate is permitted to drop into position upon the screw or worm 32^a, with the part 44, in the path of the shoulders 45. Stationary supports 46, 46^a, extend up from the base plate A¹ and support the shift plates 42, 43, under certain conditions, and movable supports 47, 47^a, support them under other conditions, as will appear later.

The movable supports 47, 47^a, are shown as formed upon a lever 35, fulcrumed on the base plate at 36, and said pivotal connection may be formed by a vertical pivot pin 36^a, secured in the base plate A¹, and extending up through the lever 35, and through a lug or ear 36^b, struck up from said lever (see Figs. 1 and 2). A pin 37^a, secured to the base plate A¹, extends up through an elongated transverse slot 37^b, in the lever 35, and limits the oscillatory movement of said lever. The support 47^a, of said lever is shown in Fig. 1, as directly supporting the shift plate 42, while the stationary support 46, is directly supporting the shift plate 43. This takes place while the tone arm travels in the direction of the arrow a.

For releasing either shift plate 42, 43, from its movable support 47, or 47^a, improved shifting mechanism is provided which comprises a shift bar 38, which is connected to the lever 35 and slidably supported in brackets 39^a, that project up from the base plate A¹, and abutment members 40, 41, adjustably mounted on the shift bar 38. Conveniently said abutment members 40, 41, may be formed with laterally projecting ears 41^a, that are perforated to receive the shift bar 38, and one of said ears 41^a, of each abutment member terminates at its lower edge in an upcurled portion 41^b, that engages with the lower edge of the shift bar 38. For locking the abutment members 40, 41, to the shift bar at any place along its length, I provide each with a round rod 40^a, which rests upon the shift bar 38, and extends through perforations in the ears 41^a, of the abutment members. At the place where said rod 40^a, extends through said ears, it is formed with eccentrically disposed portions 40^b, that turn in said ears, so that by turning the rod in the proper direction, it will be caused to bear down upon the shift bar 38, to thereby clamp the ears 41^a, upon the shift bar. The up-curved end 41^b of one of the ears 41^a bears against the underside of the bar, 38, with a spring pres-

sure, and when the rod 40^c is turned to clamp the abutment member to the bar 38, this spring pressure is increased, whereby the abutment member is firmly clamped to the bar. The outer end of each rod 40^c, is bent at right angles to the main portion to provide a handle 40^e, whereby the rod portion 40^c, may be turned, and whereby the abutment members may be adjusted back and forth upon the shift bar 38. In the case of the abutment member 40, the rod 40^c, is shown as being somewhat longer than the rod 40^c, of the abutment member 41, and it is shown as having its outer end rotatively supported in an ear or bracket 38^b, which extends up from the base plate A¹. It is obvious that by turning either rod 40^c, to loosen the grip between the abutment member, and shift bar, the abutment member may be slid along the shift bar 38, to vary the location of said abutment member to thereby accommodate record disks of different diameters. The roller carrying arm 23, moves between the abutment members 40, 41, and when it has practically reached the limit of its movement in either direction it strikes one or the other of the abutment members, depending upon which direction it is moving, and swings the lever 35, upon its fulcrum, thereby moving one of the supports 47, 47^a, into position where the plate 42, or 43, may drop off the support into position to be engaged by one of the shoulders 45, by the worm or screw 32^a. The control mechanism for controlling the number of times that the repeat mechanism is to operate, comprises a brake shoe 50, which is arranged to act upon the edge of the turn table and arrest its movement by frictional engagement therewith. In the form of the invention shown in the drawing, said brake shoe 50, is carried by a setting disk or dial 51, which is frictionally connected with a toothed or ratchet wheel 52. The shaft or spindle 28, of the frame C, has a pawl or detent 53, upon its end which is arranged to enter the notches between the teeth of the toothed wheel 52, and to partially rotate said toothed wheel each time that the frame C, is shifted to the right, as viewed in Fig. 1. Said pawl or detent 53, is here shown in the simple form of a crank arm upon the end of the spindle 28, and said crank arm is rocked back and forth each time that the frame C, is turned upon its axis to raise and lower the track 27, and as a consequence, the toothed wheel 52, is advanced one step. The frictional connection between the setting disk or dial 51, and the toothed wheel 52, may comprise a screw 54, a stationary plate 55, which is secured to the top A of the cabinet, and supports the setting mechanism, a washer or spacing member 56, a knurled button or head 57, threaded upon the upper end of the screw 54, and a spring washer 58, which is inserted between the toothed wheel 52, and a plate 59. The screw is non-rotatively connected with the plate 59, and the spacing member 56, is screwed upon the screw 54, and turns therewith. By tightening up the knurled button or head 57, friction is created between the plate 59, spring washer 58, and toothed wheel 52; between the toothed wheel 52, stationary plate 55, and spacing member 56, and between said spacing member 56, setting disk or dial 51, and knurled button 57. A pointer 60, is placed adjacent the setting disk or dial 51, and enables the user to set the disk at any place along the numbered portion thereof to cause the repeat mechanism to repeat as many times as is desired. The numbers upon the disk or dial 51, correspond to the location and number of notches in the toothed wheel 52.

A shoulder 61, is provided upon one of the members of the setting mechanism and is here shown as comprising a pin secured in the spacing member 56, and said shoulder 61, is arranged to engage one arm of a lever 62, pivotally supported on the top A, as at 63, with its other arm in engagement with the shift bar 38. The shoulder 61, is located at such a position that when the brake shoe 50, engages with the turn table to stop the same, the shoulder 61, engages the long arm of the lever 62, and draws the shift bar 38, toward the right, as viewed in Fig. 1, thereby swinging the long end of the lever 35, toward the left and bringing the right hand edge of the elongated slot 37^b, against the upstanding pin 37^a, thereby locking the parts until the setting disk is again moved to set the mechanism for repeating.

Where an electric motor is employed instead of a spring motor for driving the turn table, circuit breaking means may be employed for breaking the motor circuit at the instant that the mechanism has repeated the predetermined number of times, and this circuit breaking means may comprise the plate 59, and two terminals 64, 64, which are supported in position to contact with the plate 59. Said plate 59, may have a gap 65, located in position to register with the terminal 64, and thereby break the circuit when the setting mechanism has reached the stop position it occupies when the brake 50, frictionally contacts with the turn table.

A slightly modified form of the adjustment mechanism for limiting the range of movement of the tone arm is shown in Fig. 10. In this view, the shift bar is seen at 38¹, and the abutment at 41¹, which abutment comprises a piece of wire bent to form an upstanding loop which grips the shift bar 38¹, and a lengthwise extending portion 41², which terminates in coil 41³, twisted around the shift bar 38¹. The abutment member, as 130

shown in this modified form of the invention, is held upon the shift bar by friction and is capable of being held thereon at any position of adjustment.

In the operation of the device, the setting disk 51, is turned in a "clock wise" direction to bring any of the indicating characters thereon in register with the pointer 60. The phonograph mechanism is thereupon started which causes the turn table to rotate to the direction of the arrow *b* in Fig. 1, causing, as a consequence, movement of the tone arm and parts carried thereby, including the arms 23, 25, in the direction of the arrow *a*, during which time the selection is reproduced in the usual manner. At this time the track 27, is in its lowermost position, thereby permitting the needle or stylus to follow the groove on the record disk. When the needle finally approaches the end of the groove on the record disk, the arm 23, engages the abutment member 49, moves the same and therewith the shift bar 38, toward the left, as viewed in Fig. 1, and swings the long end of the lever 35, toward the right, bringing the supporting member 47, thereof beyond the adjacent edge of the shift plate 42, and permitting the part 44, thereof to drop upon the top of the worm or screw 32, in position to be engaged by one of the shoulders 45, thereof, wherupon, said shoulder engages said part 44, and shifts the frame C, toward the left, bringing the finger 33, of said frame into engagement with the head of the screw 32^a, causing a consequent upward movement of the arm 31^a, and track 27. This raises the roller 26, arm 25, bringing the friction roller 48, into frictional engagement with the under side of the turn table and, at the same time, the sound box lifting arm 23, is swung upward, thereby lifting the needle out of engagement with record disk. While the frame C, is being shifted to the left by one of the shoulders 45, striking the part 44, of shift plate 42, said part 44, rides over the edge of the screw 32^a, and the shift plate thereafter falls upon the stationary support 46^a, while the shift plate 43, rides upon the support 46, and the part 44, of said plate 43, comes to a position over the screw but above the plane of travel of the shoulders 45. The shift plate 43, finally reaches a place over the support 47, of the lever 35. As the finger 33, and its arm travels down the screw, the plate 42 fulcrums on the support 46^a, and its free end is swung up to a position higher than the movable support 47^a, and the shift plate 43, fulcrums on the support 46, and its free end swings down until it rests on the movable support 47, and it is lifted free of the stationary support 46, the part 43, remaining above the plane of the shoulders 45. The continued rotation of the record disk causes bodily movement of the friction roller 48,

toward the right, thereby swinging the arms 22, 25, tone arm 13, and parts carried thereby toward the right until the arm 23, engages the abutment member 41. During the time that the roller 48, moves toward the right to return the tone arm to its initial position, the frame C, is in its position to the left, and the shift plate 43, rests upon the movable support 47. As soon as the arm 23, engages and moves the abutment member 41, toward the right, the shift bar 38, is moved toward the right and the long end of the lever 35, swung toward the left, thereby releasing the shift plate 43, from its support 47, permitting the part 44, thereof, to drop upon the worm or screw, to be engaged by one of the shoulders 45, thereof, wherupon said shift plate 43, and the frame C, are shifted toward the right, thereby bringing the finger 34, into engagement with the upper end of the thread of the screw 32^a, which immediately turns the frame C, back into its original position from which it started. The endwise movement of said frame C, just described, brings the pawl or detent 53, into one of the notches of the toothed wheel 52, and the downward oscillatory movement of the track of said frame C, causes said detent 53, to swing in a direction to turn said toothed wheel one step, thereby bringing the brake shoe 50, one step nearer the record disk. As soon as the finger 34, reaches the bottom of the worm or screw 32^a, and the track reaches its lowermost position, the arms 23, 25, have been lowered, and therewith, the sound box and needle, whereby the needle is permitted to again enter the groove and repeat the selection. This action is continued until the brake shoe engages with the edge of the turn table and the shoulder 41, engages the lever 32, shifts the bar 38, toward the right, swinging the edge of the slot 37^a, against the pin 37^a, and locking the parts in locked position.

More or less variation of the exact details of construction is possible without departing from the spirit of this invention; I desire, therefore, not to limit myself to the exact form of the construction shown and described, but intend in the following claims to point out all of the invention disclosed herein.

I claim as new, and desire to secure by Letters Patent:

1. Repeating mechanism for phonographs, comprising a horizontally and vertically oscillating arm arranged to be secured to the tone arm of a phonograph, a friction roller carried by said arm in position to engage the lower face of the turn table of a phonograph, a reproducer lifting arm operatively connected with said first mentioned arm to move in unison therewith, an oscillatory and reciprocatory frame having a track for sup-

porting said first mentioned arm, a worm secured to and rotating with the turn table spindle, said frame being adapted for engagement with said worm on opposite sides 5 thereof to effect oscillation of the frame, shift plates fulcrumed on said frame, members on said worm coöperating with parts on said shift plates for reciprocating said frame, stationary supports for said shift 10 plates, movable supports for said shift plates, and operative connections for said movable supports actuated by said first mentioned arm.

2. In repeating mechanism for phonographs, a worm mounted on the turn table spindle of a phonograph, an oscillatory and reciprocatory frame having fingers adapted to engage the thread of said worm, shift plates pivotally mounted on said frame, co-acting elements on said worm and shift plates for reciprocating said frame, stationary supports for said shift plates, movable supports for said shift plates, a shift bar, means for shifting said shift bar in either 25 direction, and operative connections between said shift bar and movable supports.

3. In repeating mechanism for phonographs, a worm mounted on the turn table spindle of a phonograph and having a shoulder thereon, an oscillatory and reciprocatory frame having fingers adapted for engagement with said worm, shift plates pivotally mounted on said frame and having parts adapted to be engaged by said shoulders whereby the frame is reciprocated, stationary supports for said shift plates, a lever having movable supports for said shift plates, a shift bar connected with said lever and means for moving said shift bar end- 40 wise in both directions.

4. In repeating mechanism for phonographs, a shift bar, an abutment member slidably mounted on said shift bar and a clamp rod rotatively mounted in said abutment member on eccentric portions, whereby the abutment member is clamped upon said shift bar.

5. In repeating mechanism for phonographs, a shift bar, an abutment member having perforated ears slidably mounted on said shift bar and a clamp rod having eccentric portions rotatively mounted in said ears above the shift bar.

6. In repeating mechanism for phonographs, a shift bar, an abutment member having perforated ears mounted upon said shift bar, one of said ears being formed on its lower end with an upturned spring portion bearing against the lower edge of the shift bar, and a clamp rod having eccentric portions rotatively mounted in said ears.

7. In repeating mechanism for phonographs, a shift bar, an abutment member slidably mounted thereon and having spring pressure against said shift bar, and clamp-

ing means for clamping said abutment member on said shift bar against said spring pressure.

8. In repeating mechanism for phonographs, an oscillatory and reciprocatory frame, means operated by the turn table spindle of a phonograph for oscillating and reciprocating said frame, a pawl carried by said frame, a toothed wheel actuated by said pawl, and a brake shoe frictionally connected to and moving with said toothed wheel and adapted to be brought into frictional engagement with the turn table by said pawl.

9. In repeating mechanism for phonographs, an oscillatory and reciprocatory frame, means upon the turn table spindle of a phonograph for oscillating and reciprocating said frame, a pawl carried by said frame, a toothed wheel adapted to be actuated by said pawl, and a setting dial frictionally secured to said toothed wheel and having a brake shoe arranged for frictional engagement with the turn table.

10. In repeating mechanism for phonographs, an oscillatory and reciprocatory frame, means controlled by the turn table spindle of a phonograph for oscillating and reciprocating said frame, a pawl carried by said frame, a toothed wheel adapted to be intermittently rotated by said pawl, a setting dial having a brake shoe adapted for frictional engagement with the turn table, and frictional connecting devices between the toothed wheel and dial.

11. In repeating mechanism for phonographs, an oscillatory and reciprocatory frame, means carried by the turn table spindle of a phonograph for oscillating and reciprocating said frame, a pawl carried by said frame, a toothed wheel arranged to be intermittently rotated by said pawl, a stationary plate, a setting dial having a brake shoe adapted for frictional engagement with the turn table, and friction means between said toothed wheel, setting dial and stationary plate.

12. In repeating mechanism for phonographs, an oscillatory and reciprocatory frame, means carried by the turn table spindle of a phonograph for oscillating and reciprocating said frame, a pawl carried by said frame, a toothed wheel arranged to be intermittently rotated by said pawl, a setting dial frictionally connected to said toothed wheel, a brake shoe adapted to be intermittently moved by said toothed wheel and arranged to frictionally engage with said turn table, terminal contact pieces of an electric motor operating circuit, and a contact piece having a gap therein and moving with said toothed wheel.

13. In repeating mechanism for phonographs, an oscillatory and reciprocatory frame, means for oscillating and reciprocating

ing said frame, a pawl carried by said frame, a toothed wheel adapted to be intermittently rotated by said pawl, a stationary supporting plate against which said toothed wheel bears, a spacing member bearing against said stationary plate, a setting dial bearing against said spacing member, a screw extending through said toothed wheel, stationary plate, spacing member and setting dial, a button threaded upon said screw, and a brake shoe driven by said toothed wheel adapted to frictionally engage with the turn table of the phonograph.

14. In repeating mechanism for phonographs, an oscillatory and reciprocatory frame, means for oscillating and reciprocating said frame, including an oscillatory lever, stops for limiting the movements of the lever, setting mechanism operated by said frame, a shift bar for actuating said oscillatory lever, and a lever pivotally connected to said shift bar and adapted to be engaged by an element of the setting mechanism, to lock the parts against accidental movement.

MAGNUS W. TURNQUIST.
